DESIGN FOR A COMMODE

Henry L. Johnson, Bunnell, Fla.

Application February 23, 1944, Serial No. 112,685

Term of patent 14 years

(Cl. D4—5)

To all whom it may concern:

Be it known that I, Henry L. Johnson, a citizen of the United States of America, residing at Bunnell, county of Flagler, and State of Florida, have invented a new, original, and ornamental Design for a Commode, of which the following is a specification, reference being had to the accompanying drawing, forming a part thereof wherein:

I claim:

The ornamental design for a commode, as shown.

HENRY L. JOHNSON.
